UNITED STATES PATENT OFFICE.

WILLIBALD TRINKS, OF PITTSBURGH, PENNSYLVANIA, ASSIGNOR TO TATE-JONES & CO., INC., OF LEETSDALE, PENNSYLVANIA, A CORPORATION OF PENNSYLVANIA.

HEATING FURNACE.

Application filed April 12, 1920. Serial No. 373,445.

To all whom it may concern:

Be it known that I, WILLIBALD TRINKS, a citizen of the United States, residing in Pittsburgh, in the county of Allegheny, 5 State of Pennsylvania, have invented a new and useful Improvement in Heating Furnaces, of which the following is a specification.

My improvement relates to the type of 10 furnace in which the material to be heated is carried around on an annular horizontal hearth which revolves about a vertical axis. This type of furnace has appealed to manufacturers, because it is conducive to economy 15 of both fuel and labor. While the rotating-hearth furnace has been a commercial success in small sizes, and particularly so with heating by electrical means, furnaces with large hearths have been built, but have in 20 most cases been dismantled and given up, principally on account of breakage, but also on account of unequal distribution of temperature in the case of heating by combustion. The present specification concerns it- 25 self principally with the mechanical strength of rotating hearths and with other features contributing to safety against breakage.

In the drawings, Figure 1 is a vertical cross-section thru the center of the furnace, 30 taken in its left hand half thru one of the shafts for entering air, and taken in its right hand half thru the furnace door and thru one of the air discharge ducts. Figure 2 is a plan view, partly in section under the 35 hearth, and in part a top view of the furnace. Figure 3 is an elevation of one of the adjustable bearings; Figure 4 is a front view of the same bearing, while Figure 5 shows the adjusting wedge. Like numerals refer 40 to like parts thruout the different views.

In the illustrations, 1 is the rotating hearth which is built up of metal, with refractory material in the top. 2 are supporting rollers or wheels, which, in my pre- 45 ferred plan, are adjustable up and down by means of wedges 3 and screws 4. For the sake of simplicity, wedges 3 and screws 4 are omitted in Figure 1. The wedges rest on metallic supports 5. The latter are so 50 deep and are spaced so far apart that they leave between them a walking space 6. The outer row of wheels carries flanges against which a depending part of the hearth bears in case of radial thrust. Air is admitted to 55 this walkway thru a plurality of air inlet

ducts 7, which are spaced around the circumference of the furnace. The openings to the vertical air shafts may be regulated by partly covering them. Ducts 8 connect the walkway 6 to the stack 9. Fuel is introduced into the furnace thru burners 10, but the method of providing heat for the furnace and of distributing it evenly is not a part of this invention.

The operation of that part of the furnace 65 which is concerned with the present invention is as follows:—Before the furnace is lighted, all rollers 2 are adjusted to bear uniformly, while the hearth is rotating. This work requires the presence of a man under 70 the hearth and necessitates shifting of the different sections of the furnace up or down relatively to each other in order to make all wheels bear in any portion of the hearth. The furnace is then lighted, and loaded with 75 the average weight which is to be heated.

It is during this time that the value 80 of my arrangement becomes evident. Large, slowly-rotating hearths have different temperatures at different parts of the circumference, because cold material is charged at one spot and hot material is removed at another spot. A heat wave is sent into the top of the hearth by this action at a given 85 spot, and the hearth warps in such a manner that certain spots—fixed with regard to space—are raised and others are depressed, in a manner which cannot be determined by calculation. If the initial adjustment of the rollers is maintained, the table cracks, be- 90 cause only a few of the supports will bear. A cracked table sticks, and in a short time the whole driving mechanism is ruined. It is this action which has heretofore kept furnaces with large rotating hearths from 95 being successful, although many patents have been granted on that type of furnace.

The problem can be solved only by up and down adjustment of the rollers while the furnace is in operation. To that end I pro- 100 vide under the table 1 sufficient space 6 for a man to work between the supporting bearings, and I provide entrance shafts 7 leading to the space under the table. The tempera- 105 ture in which a man can work for any length of time is much below the temperature in which the rollers under the furnace can work right along, but there are limits to that latter temperature. It is, therefore, very de- 110 sirable to adjust both the normal operating

temperature under the hearth and the temperature which is to prevail during periods of inspection and repair. To that end I partly cover each vertical shaft 7, for instance with sheets, so that the flow of air through the space 6 may be regulated. I also provide ducts 8 leading from said space 6 to the stack 9. There being a plurality of air shafts 7 and of ventilator ducts 8, a positive air circulation is obtained. Further regulation of the temperature in space 6 is obtained by partial obstruction of any one or all of ducts 8. By these various means, a temperature of 400 to 450 degrees Fahrenheit can be maintained during regular operation; while a working temperature can be maintained during periods of inspection and adjustment.

The walkway 6 between the bearings 5 is made deep enough for a man to walk in a stooped position.

The passing of the flame or flue gases from the heating chamber above the rotating table into the inspection pit below said table is prevented by sand seals 11 at the inner and outer edges as shown in the illustration. The sand seals are necessary for the control of the temperature below the hearth, it being understood that the temperature below the hearth is kept just as high as safe operation will permit, for the purpose of reducing heat loss through the hearth.

What I claim as new is:

1. In a heating furnace with an annular, horizontal, rotating hearth table, independent vertically adjustable supports for said

table, an enclosed inspection pit below said table, sand seals between the heating chamber and the inspection pit, a plurality of regulable air admission openings at the outer circumference of the inspection pit, and a plurality of ducts leading from said pit to a central stack.

2. In a heating furnace with an annular, horizontal, rotating hearth table an inner row of wheel supports, an outer row of wheel supports, means for independently adjusting the vertical height of the wheel supports, sand seals at the inner and outer edges of the hearth, means for taking up radial thrust caused by the driving mechanism, and means for regulating the temperature below the hearth.

3. In a heating furnace with an annular, horizontal, rotating hearth table, independently adjustable roller supports for said table, a closed inspection pit below said table, a plurality of regulable air admission openings at the outer circumference of the pit, a plurality of ducts leading from said pit to a central stack, and sand seals between the spaces above and below the hearth.

4. In a heating furnace with an annular, horizontal, rotating-hearth table, independently vertically adjustable roller supports for said table, means for sealing the space above the table from the space below the table, a walkway underneath said hearth table, and means for regulating the temperature below the hearth table by means of adjustable air circulation.

WILLIBALD TRINKS.
